CLAIM

The ornamental design for a heat press temperature controller, as shown.

DESCRIPTION

FIG. 1 is a front right perspective view of a heat press temperature controller showing my new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the drawings depict unclaimed portions of the heat press temperature controller.
